[57] ABSTRACT

An alkaline aqueous cleaning solution for removing residue from silk screen stencils and containing active components for removal of residual ink, as well as active components for removal of residual stencil barrier areas. The working solution is inert to the silk utilized in the woven screen, as well as to the metallic frame support.

7 Claims, No Drawings

SILK SCREEN CLEANER COMPOSITION

BACKGROUND OF THE INVENTION

The present invention relates generally to a formulation for the cleaning and re-conditioning of silk screens, and more particularly to an improved formulation for the simultaneous removal of residual ink and residual stencil masking material from the silk weave. The formulation of the present invention is inert toward the woven silk as well as to the metallic frames utilized to support the weave. 10

Silk screen techniques are widely used in certain areas of technology including graphics, printed circuitry preparation, and the like. Traditionally, the silk weave is maintained or retained in a metallic frame, and a stencil masking material is applied thereto. The masking material traditionally includes polyvinyl acetate-polyvinyl alcohol as a binder together with a photosensitive substance such as sodium chromate, sodium bichromate, or a diazo material. Upon appropriate exposure of the photosensitive material to light, the mask image is prepared and the latent nonpolymerized materials are washed from the screen weave, and the mask is then ready for use. 15

While in use, a number of paints or other materials are employed to properly prepare the image on the surface of the substrate or other medium to receive print. Examples of inks which are traditionally used are vinyls, alkyds, latex materials, thermosetting acrylics, lacquers including pigmented and non-pigmented materials, enamels, thermosetting polyethylene terephthalate, polyethylene or polypropylene, along with adhesives. In addition, epoxy-base materials are also utilized. 20

Following use, it is desirable to remove the residual ink along with any residual stencil masking. In the past, this has traditionally been accomplished by utilizing a two-step process wherein a solvent such as toluol, methyl ethyl ketone, acetone, mineral spirits, or mixtures thereof to dissolve out any of the residual ink. The polyvinyl acetate stencil masking material is resistant to these solvents, and hence a second operation was necessary wherein an aqueous solution of chlorine, preferably from 5 percent to 7 percent chlorine, was utilized to digest the polyvinyl acetate residue. Such concentrations of chlorine are readily available from commercial bleach mixtures. These operations are time consuming and costly, and hence are not particularly desirable. 25

In certain instances, conventional paint strippers have been utilized, however the high pH due to high lye content normally adversely affects the aluminum frames. Low alkaline cleaners have been proposed, however they are undesirable in that the emulsion material may be removed, but the residual paint is not. The present invention overcomes these disadvantages by making it possible to utilize a single solution which removes residual ink and residual stencil masking without adversely affecting the metallic aluminum frames. 30

SUMMARY OF THE INVENTION

In accordance with the present invention, an aqueous solution is employed for removing residue from silk screen stencils, wherein the solution contains an alkaline hydroxide along with other components which function as dispersants for pigments and other soils, solvents for the film-forming resins, and an inhibitor to protect the surface of the metallic frames, normally

aluminum. The composition provides a working solution which rapidly removes residue from the screen surface, holds the residues in suspension; all of this being accomplished without adversely affecting either the silk weave substance or the metallic frame. 5

Therefore, it is a primary object of the present invention to provide an improved cleaner material for removing residual ink and residual stencil masking materials from silk screens.

It is yet a further object of the present invention to provide an improved solution for the effective removal of residual ink and stencil masking material from woven silk screens, with the formulations of the present invention being capable of effectively removing this residue without adversely affecting either the silk weave or the metallic frames employed for the weaves. 10

Other and further objects of the present invention will become apparent to those skilled in the art upon a study of the following specification and appended claims.

DESCRIPTION OF THE PREFERRED EMBODIMENT

In accordance with the preferred embodiment of the present invention, an alkaline concentrate is prepared having the following formulation:

Component	Percent by Weight
Potassium hydroxide	3.970
Tetrapotassium pyrophosphate	9.000
Sodium silicate solids	6.250
Sodium gluconate	1.875
Sodium ligno sulfonate	0.625
Diethylene glycol monobutyl ether	5.000
Diethylene glycol monoethyl ether	25.000
Octylphenoxyethanol	0.565
Balance water	

This particular formulation is utilized as a concentrate which is further diluted with water to prepare the ultimate working solution. In this connection, the concentrate is incorporated in water in a quantity ranging from between 10 percent and 60 percent of concentrate, balance water. 40

For performing the actual cleaning operation, the working solution is placed in a tank and the screen desired to be cleaned is immersed in the tank for a period of approximately 15 minutes. Such immersion is normally sufficient to remove approximately 95 percent of the soil present on the screen, and effectively softens the polyvinyl acetate resist. Obviously, if the material were to be heated, the immersion time could be shortened. 45

Thereafter, the screen is subjected to a spray rinse with the same working solution, with the rinse preferably being achieved with a nozzle capable of dispensing a discharge of approximately 2 gallons per minute at 500 psi. This will effectively remove the soil from the screen and after rinsing and drying, the screen is suited for re-use. 50

In certain instances, silk screens are prepared utilizing multi-filament or monofilament polyester or nylon materials. The working solution of the present invention has been found to be non-harmful to these fabrics. Also, in addition to aluminum, steel and wood frames are in use, neither of which are adversely affected by the working solutions of the present invention. 55

The working solutions of the present invention are operational without requiring the use of flammable solvents or chlorine bleaches, both of which are difficult for handling. Also, the surface active agents which are employed in the material are biodegradable, and thus provide an advantage in ultimate disposal.

The formulations have long tank life, and exceptionally long shelf life. Thus, unusual precautions are not required for use.

In the working solution, elevated temperatures are not an absolute requirement, however it has been found that temperatures in the range of from 180° F. to 200° F. are desirable from the standpoint of cleaning efficiency.

In the preparation of dilute working solutions, it has been found that a workable range may be expressed as follows:

Component	Percent by Weight
Potassium hydroxide	.3 to 2
Tetrapotassium pyrophosphate	.7 to 4
Sodium silicate solids	.5 to 3
Sodium gluconate	.15 to 1
Sodium ligno sulfonate	.05 to .3
Diethylene glycol monobutyl ether	.25 to 2.5
Diethylene glycol monoethyl ether	2 to 20
Nonionic surface active agent selected from the group consisting of octyphenoxyethanol and nonylphenoxyethanol	.04 to .4
Balance water	

For most operations, however, and for the preparation of a solution which is usable with all inks, particularly those as set forth hereinabove, the following formulation is recommended:

Component	Percent by Weight
Potassium hydroxide	.5 to 1.5
Tetrapotassium pyrophosphate	1 to 3
Sodium silicate solids	1 to 2
Sodium gluconate	.2 to .5
Sodium ligno sulfonate	.1 to .2
Diethylene glycol monobutyl ether	1 to 1.5
Diethylene glycol monoethyl ether	3 to 7
Nonionic surface active agent selected from the group consisting of octyphenoxyethanol and nonylphenoxyethanol	.05 to .15
Balance water	

This compositional range has been found particularly desirable for use with paints of the following composition or formulation; vinyls, alkyds, latex materials, thermosetting acrylics, lacquers including pigmented and non-pigmented materials, enamels, thermosetting polyethylene terephthalate, polyethylene or polypropylene, along with adhesives.

In certain instances, highly cured epoxy-base paints are removed with a certain amount of difficulty, however the composition of the present invention is useful in removing epoxy-base paints which have not become totally or completely cured on the surface of the screen.

In the formulation, potassium hydroxide is preferred, however it is understood that the hydroxide may be an alkaline earth hydroxide selected from the group consisting of sodium hydroxide and potassium hydroxide. This component in the formulation is an alkaline donor which enhances the cleaning function, as well as pro-

viding a neutralization source for acidic soil. Furthermore, potassium hydroxide functions as a silicate stabilizer as a potassium ion donor in the system.

The tetrapotassium pyrophosphate, in addition to functioning as a water softener in the working solution, is a strong dispersent for pigments dissolved in the cleaning operation.

Sodium gluconate, also identifiable as the sodium salt of 2, 3, 4, 5, 6 pentahydroxy-1-hexanoic acid, and the sodium ligno sulfonate function as strong dispersents for removed soil, and also operate to complex metallic ions present in the soils. In addition, these materials function as an anti-scale and sludge conditioner.

Sodium lignosulfonate is the sodium salt of lignin sulfonic acid. While the exact structure of lignin has not as yet been determined, it is known to be a polymer with an average molecular weight of about 10,000. The repeating monomer unit is guar-acyl propane having the structural formula as follows:

Sodium silicate solids are employed having a $\text{Na}_2\text{O}/\text{SiO}_2$ ratio of 1:1.6 up to about 1:3.22. This range of materials has been found to be useful. The sodium silicate provides a strong corrosion inhibitor for soft metals such as aluminum, and also provides for a substantial degree of detergency.

The diethylene glycol monobutyl ether and the diethylene glycol monoethyl ether are employed for their properties of strong penetrants and solvents for the film-forming resins. They have low odor, are water soluble, with high boiling points.

The nonionic surface active agent is preferably selected from the group consisting of octyphenoxyethanol and nonylphenoxyethanol. These materials have a high cloud point (normally above 100° C.), are biodegradable, and alkaline stable. They tend to reduce the surface tension and therefore aid in rinsing after film removal. Other nonionic or anionic surface active agents may be used if desired. Anionic surface active agents which may be utilized successfully are sodium alkylbenzene sulfonate materials which are, of course, widely used for these purposes. These materials are commercially available.

These materials are a class of synthetic anionic surface active agents represented by the general formula:

wherein R is a straight or branched chain saturated hydrocarbon group having from about 8 to about 18 carbon atoms, such as a straight or branched group, such as octyl, nonyl, decyl, dodecyl and the like; A is either oxygen, sulfur, a carbonamide group, thiocarbonamide group, a carboxylic group or thiocarboxylic ester group, x is an integer from 3 to 8 and M is preferably sodium, but may be either hydrogen, potassium, ammonium, an organic amine such as ethanolamine, diethan-

olamide, triethanolamine, ethylene diamine or the like.

Compounds illustrative of the sulfated oxyethylated alkyl phenol class of anionic surface active agents include ammonium nonylphenoxy tetraethoxy sulfate, sodium dodecylphenoxy triethoxy sulfate, ethanolamine decylphenoxy tetraethoxy sulfate and potassium octylphenoxy triethoxy sulfate. These materials are also commercially available.

Working solutions having the following specific formulations were prepared.

EXAMPLE 1

Component	Percent by Weight
Potassium hydroxide	0.397
Tetrapotassium pyrophosphate	0.9
Sodium silicate solids ($\text{Na}_2\text{O}/\text{SiO}_2 = 1:3.22$)	0.625
Sodium gluconate	0.1875
Sodium ligno sulfonate	0.0625
Diethylene glycol monobutyl ether	0.5
Diethylene glycol monoethyl ether	2.5
Octylphenoxyethanol	0.0565
Balance water	

This formulation provided good results.

EXAMPLE 2

Component	Percent by Weight
Potassium hydroxide	1.99
Tetrapotassium pyrophosphate	4.5
Sodium silicate solids ($\text{Na}_2\text{O}/\text{SiO}_2 = 1:1.6$)	3.125
Sodium gluconate	0.938
Sodium ligno sulfonate	0.313
Diethylene glycol monobutyl ether	2.5
Diethylene glycol monoethyl ether	12.5
Nonylphenoxyethanol	0.238
Balance water	

This formulation provided good results.

EXAMPLE 3

Component	Percent by Weight
Potassium hydroxide	1.32
Tetrapotassium pyrophosphate	3.0
Sodium silicate solids ($\text{Na}_2\text{O}/\text{SiO}_2 = 1:1.6$)	2.08
Sodium gluconate	0.625
Sodium ligno sulfonate	0.208
Diethylene glycol monobutyl ether	1.67
Diethylene glycol monoethyl ether	8.33
Sodium dodecylphenoxy triethoxy sulfate	0.188
Balance water	

This formulation provided good results.

EXAMPLE 4

Component	Percent by Weight
Potassium hydroxide	1.32
Tetrapotassium pyrophosphate	3.0
Sodium silicate solids	2.08
Sodium gluconate	0.625
Sodium ligno sulfonate	0.208
Diethylene glycol monobutyl ether	1.67
Diethylene glycol monoethyl ether	8.33
Potassium octylphenoxy triethoxy sulfate	0.188
Balance water	

This formulation provided good results.

The composition of the present invention as well as the techniques employed are usable over a wide range of materials and working conditions. The formulations provide for efficient and effective cleaning of silk screens.

I claim:

1. An alkaline aqueous cleaning solution for removing residue from silk screen stencils and having the following formulation:

Component	Percent by Weight
15 An alkaline earth hydroxide selected from the group consisting of sodium and potassium hydroxides	.3 to 2
Tetrapotassium pyrophosphate	.7 to 4
Sodium silicate solids ($\text{Na}_2\text{O}/\text{SiO}_2 = 1:1.6$ to 1:3.22)	.5 to 3
Sodium gluconate	.15 to 1
20 Sodium ligno sulfonate	.05 to .3
Diethylene glycol monobutyl ether	.25 to 2.5
Diethylene glycol monoethyl ether	2 to 20
Surface active agent selected from the group consisting of nonionic and anionic surface active agents	
Balance water	.04 to .4

2. The alkaline aqueous cleaning solution as defined in claim 1 being particularly characterized in that said alkaline earth hydroxide is potassium hydroxide.

3. The alkaline aqueous cleaning solution as defined in claim 1 wherein said surface active agent is selected from the group consisting of octylphenoxyethanol and nonylphenoxyethanol.

4. The alkaline aqueous cleaning solution as defined in claim 1 being particularly characterized in that said solution has the following formulation:

Component	Percent by Weight
40 Potassium hydroxide	.5 to 1.5
Tetrapotassium pyrophosphate	1 to 3
Sodium silicate solids	1 to 2
Sodium gluconate	.2 to .5
Sodium ligno sulfonate	.1 to .2
Diethylene glycol monobutyl ether	1 to 1.5
Diethylene glycol monoethyl ether	3 to 7
45 Nonionic surface active agent selected from the group consisting of octylphenoxyethanol and nonylphenoxyethanol	.05 to .15
Balance water	

5. An alkaline aqueous cleaning solution concentrate for the preparation of working solutions to remove residue from silk screen stencils and having the following formulation:

Component	Percent by Weight
60 Potassium hydroxide	3.970
Tetrapotassium pyrophosphate	9.000
Sodium silicate solids	6.250
Sodium gluconate	1.875
Sodium ligno sulfonate	0.625
65 Diethylene glycol monobutyl ether	5.000
Diethylene glycol monoethyl ether	25.000
Octylphenoxyethanol	0.565
Balance water	

6. The method of cleaning silk screen printing stencils after use which comprises:

a. immersing said stencil in a solution of the following formulation:

Component	Percent by Weight in Water
An alkaline earth hydroxide selected from the group consisting of sodium and potassium hydroxides	0.3970 to 1.588
Tetrapotassium pyrophosphate	0.9000 to 3.600
Sodium silicate solids (Na ₂ O/SiO ₂ - 1:1.6 to 1:3.22)	0.6250 to 2.500
Sodium gluconate	0.1875 to 0.750
Sodium ligno sulfonate	0.0625 to 0.250
Diethylene glycol monobutyl ether	0.5000 to 2.000
Diethylene glycol monoethyl ether	2.5000 to 10.000

-Continued

Component	Percent by Weight in Water
5 Surface active agent selected from from the group consisting of octylphenoxyethanol and nonylphenoxyethanol Balance water	0.0565 to 0.226

10 b. and thereafter rinsing and drying.

7. The method of cleaning silk screen printing stencils as defined in claim 6 being particularly characterized in that said alkaline earth hydroxide is potassium hydroxide.
